UNITED STATES PATENT OFFICE.

CHARLES THOMPSON, OF SYRACUSE, NEW YORK, ASSIGNOR OF EIGHT-FIFTHS TO C. N. HATCH AND WILLIAM H. DIETS, OF SAME PLACE.

CAR-AXLE FRAME.

SPECIFICATION forming part of Letters Patent No. 494,942, dated April 4, 1893.

Application filed September 24, 1892. Serial No. 446,848. (No model.)

To all whom it may concern:

Be it known that I, CHARLES THOMPSON, a resident of the city of Syracuse, in the county of Onondaga, State of New York, have invented a new and Improved Car-Axle Frame for and in Connection with a Sectional Car-Axle for Use upon Street Cars or Railways and other Analogous Devices, of which the following is a specification, reference being had ⁵ to therein to the accompanying drawings.

This invention relates to certain new and useful improvements in sectional axles and frames therefor and it has for its object, among others, to provide a sectional car axle ¹⁵ that can be operated in single sections or by combining two or more sections as occasion may require.

It has for a further object to rigidly support each sectional axle on a parallel plane ²⁰ and in such a manner as to overcome undue vibration at the center connection of the axles and at the same time to permit each section to operate with the least possible friction when passing around curves.

Other objects and advantages of the invention ²⁵ will appear in the following description, and the novel features thereof will be particularly pointed out in the appended claims.

The invention is clearly illustrated in the ³⁰ accompanying drawings which, with the letters of reference marked thereon, form a part of this specification and in which—

Figure 1 is a side elevation with a portion ³⁵ broken away showing my improvement as applied for instance, to a street-car. Fig. 2 is a plan of the compression-plate detached. Fig. 3 is a plan of the frame with a sectional axle therein. Fig. 4 is a side elevation of several sections combined for use as a car truck.

Like letters of reference refer to like parts ⁴⁰ in all the figures of the drawings.

Referring now to the details of the drawings by letter A designates the frame, rectangular in form as seen in Fig. 3 and provided ⁴⁵ with the central cross timber A' upon which are supported the boxes or bearings a' for the adjacent journals of the sectional axles, being supported upon the end timbers of the frame.

B are the sectional axles formed at one end ⁵⁰ with the journals b supported in the boxes or

bearings a' and at their other ends with the journals b' supported in the boxes or bearings a.

B' are extensions or projections.

C are the wheels of known construction arranged upon the axles within the frame A adjacent to the end timbers A' thereof as shown.

Referring now to Fig. 1 the application of ⁶⁰ my invention will be seen. D designates the bottom or frame of the car to the under side of which is secured the bracket E which is formed upon the arc of a circle and is provided with flanges e through which pass the ⁶⁵ bolts e' or other means which serve to secure the same to the frame of the car. This bracket has a curved slot or opening E' in which works the extension B' which is somewhat narrower than the said slot as seen in ⁷⁰ Fig. 1, for a purpose which will hereinafter be explained.

E' is a stop on the bracket. Between it and the said extension is arranged a spring F of any suitable character as for instance, a rubber block as seen in Fig. 1.

G is a box or frame connected to or extending from the front portion of the frame A and at its other end pivotally supported upon a pivot g supported in the ears h of a plate H ⁸⁰ which is provided with the longitudinal slots h' in which work the bolts I as seen best in Fig. 2, which serve to secure said plate to the car frame, as seen in Fig. 1 and not permit of longitudinal movement of the plate when ⁸⁵ occasion may require. This plate is provided with an upwardly extending portion H' which fits in a recess d' in the car frame as seen in Fig. 1 which recess is somewhat longer than the said portion H' which remaining space is occupied by the spring I' of any suitable character preferably a rubber block as seen in Fig. 1. With the parts thus arranged and the truck supposed to be moving in the direction of the arrow in Fig. 1, should the wheels meet ⁹⁵ with an obstruction or from any other cause be so acted upon as to under ordinary circumstances cause a shock, the said shock will be taken up by a spring I' and thereby prevented from being transmitted to the car. This is ⁹⁰ accomplished in the following manner: The extension B' being smaller than the slot in

55

the bracket the frame is free to be moved in the direction of the length of the car and this causes the brace G to be moved in the direction of its length which by reason of the mounting of the plate H for longitudinal movement, moves said plate to which it is connected and compresses the spring I' by engagement therewith of the extension H' all as clearly shown in Fig. 1.

10. When it is desired to combine several of these frames and sectional axles to form a truck as in Fig. 4 I secure to the frame D the brackets J which are fastened thereto in any suitable manner as by the bolts j and to these brackets I attach the connecting bar K at k. This connecting bar which may be in one or more parts rests upon the journals of extensions B' of the axles B which are inserted and held in position in the brackets L secured to the frame A all as clearly seen in Fig. 4.

Having thus described my invention, what I claim is—

1. The combination with the frame having central cross portion, of the sectional axle 25 supported in bearings on said frame and provided with extensions upon the outer sides of the end portions thereof and with wheels upon the axle within the frame, substantially as specified.

30. 2. The combination with the car frame, of a bracket secured to the under side thereof and having curved slot, the axle having a

portion riding in said slot, the axle frame and a spring held in said sliding connection between said frame and the frame of the car, 35 substantially as specified.

3. The combination with the car frame and the bracket with curved slot, of the car axle frame and axle, the latter having an extension riding in said slot, a spring acting upon 40 said extension and a brace connecting the axle frame with a spring-pressed slide plate upon the car frame, as set forth.

4. The combination with the car frame and the bracket of the axle frame with its axle 45 having extension, the spring in the bracket acting on the extension, the brace connected with the car frame with said axle frame, a plate slidably connected with the car frame and pivotally connected with said brace and 50 a spring adapted to be compressed by the employment of said plate, substantially as specified.

5. The combination with a car frame having a recess, of a plate slidably mounted on said frame and having an extension in said recess, a spring in said recess engaged by said extension and a pivotal connection between said plate and with an axle, substantially as specified.

CHARLES THOMPSON.
